UNITED STATES PATENT OFFICE.

EUSTACE E. WIGZELL, OF LONDON, ENGLAND.

STAMP-VENDING MACHINE.

No. 888,562.

Specification of Letters Patent.

Patented May 26, 1908.

Application filed February 15, 1908. Serial No. 416,151.

To all whom it may concern:

Be it known that I, EUSTACE E. WIGZELL, a subject of the King of Great Britain and Ireland, and resident of Billiter House, Billiter street, London, E. C., England, engineer, have invented a certain new and useful Improvement in Stamp-Vending Machines, of which the following is a specification.

I have a plate of metal or other suitable material upon which the working parts of this machine are mounted. On a container reel is wound two tapes in between which are placed the postage stamps either singly or in continuous lengths. This container reel is fixed opposite two drawing and delivery rollers between which the tapes are led, the top tape passing round the top drawing and delivery roller and upwards round a guide roller on to a drawing-in reel which is driven by a band off the top drawing and delivery roller. The bottom tape passing downwards round the bottom drawing and delivery roller and over a guide roller or rollers on to a drawing-in reel which is also driven by a band from the top drawing and delivery roller. The tapes are guided in their respective travels by metal troughs or channels fixed where necessary. The bottom drawing and delivery roller is fixed on a lever pivoted near the roller for closing the two rollers together or separating them for the purpose of charging the machine, the stamps being inserted in the opening in the front of the machine (referred to hereunder) and between the two drawing and delivery rollers so that when the container reel is turned round it draws in the stamps and unwinds the tape from the two drawing-in reels.

On the other side of the machine and fitted to the shaft carrying the top drawing and delivery roller, I have a lever with ratchet wheel so that when this lever is moved a given distance it turns the drawing and delivery rollers pulling the tapes and revolving the reel on which the tapes are wound a space equal to the length or width of a postage stamp, causing one stamp only to protrude through an opening (as referred to above) in the front of the machine, where it can be detached ready for use.

The lever is locked by a bolt which can be released upon an appropriate coin being inserted in a slot in the machine, or a counter can be attached so that upon every stroke of the lever a point would be registered to keep a tally of the number of stamps extracted.

A sheet of drawings accompanies this specification as part thereof.

Figure 1 is a side view showing the parts on one side of a divisional frame plate and Fig. 2 is a like view showing the parts on the other side of the same frame plate.

Like reference characters refer to like parts in both figures.

In Fig. 1 A¹ is the plate upon which the working parts of the machine are mounted. A is the container reel placed opposite the two drawing and delivery rollers H F, the tapes B and C passing between these rollers delivering the stamps D at the front of the machine. The top tape C passing round the drawing and delivery roller H and upwards round the guide roller E on to the drawing-in reel J which is driven by a band I off the drawing and delivery roller H, the bottom tape B passing downwards round the drawing roller F and the guide roller E on to the drawing-in reel K which is worked by a band L from the drawing and delivery roller H.

For charging the machine with postage stamps, the drawing and delivery roller F is pivoted to a lever G and the lever is pivoted at P so that by slackening out the screw M the lever can be lifted up in the slot N taking the pressure off the drawing and delivery rollers H F. The channels or troughs for guiding the tape or tapes are shown at O.

In Fig. 2 Q indicates the ratchet wheel with teeth at given distances apart equal to the length or width of a postage stamp. This ratchet wheel is keyed on to a shaft R which in turn is keyed at the other side of the machine to the drawing and delivery roller H. Fig. 1. Over this shaft R there is a loose sleeve S with an arm U to which a pawl V is attached and which works the ratchet wheel Q. Keyed on the loose sleeve S. I have a lever W so that when this lever is pushed forward it turns the ratchet wheel Q pulling the two tapes B and C with the stamps D in between off the container reel A so that one stamp only will protrude from the opening at the front of the machine at every stroke of the lever where it can be detached ready for use.

For regulating the distance of the travel of the tapes with the stamps in between, the arm U on the loose sleeve S comes against the stop X and on its downward motion comes against the stop Y giving a fixed distance for its travel. There is an arm T fixed on the loose sleeve S at the end of which there is a

- spring Z bringing it back to its position after being pressed forward. For releasing the lever W, I have a bolt A⁴ swung on a link B¹ one end coming against the arm U and the other against the stop C¹. When an appropriate coin is inserted in the chute D¹ it presses down the bolt A⁴ releasing the arm U and on the lever E¹ being drawn down by the rod F¹ attached to the arm U it lifts up the chute D¹ throwing the coin over the stop C¹, the bolt A⁴ falling back into its former position, preventing the lever W from being moved by the arm U, the bolt being pressed against the stop C¹. Should a smaller coin be passed through the chute D¹ it falls through the hole in the bolt G¹ and down the chute H¹ and is then thrown out at the front of the machine. To facilitate turning the rolls H and F backward, in charging the machine with stamps, a vertical slide U', Fig. 2, slidably attached to the frame plate A', is arranged to contact with the stud V' projecting rigidly from the heel end of the pawl V when the pawl carrier formed by the arm U is in its retracted position represented in Fig. 2, so as to lift the toe end of the pawl out of engagement with the ratchet wheel Q, and thus to free this wheel and the shaft R and roll H which turn therewith.
- It will be seen that this machine can be adapted for postage stamps of any face value. Having now described my invention, what I claim as new and desire to secure by Letters Patent is:
1. In a stamp vending machine, the combination with a hand lever and means for

fastening the same in different positions of a pair of feed rolls between which the stamps are inserted and delivered and one of which feed rolls is movable toward and away from the other feed roll by means of said lever, means for turning said feed rolls step by step to deliver the stamps, two tapes which pass around said feed rolls and between which the stamps are carried, a reel common to both tapes and to which one end of each tape is attached, take-up reels to which the other ends of the tapes respectively are attached, means for guiding said tapes, and means for transmitting motion to said take-up reels simultaneously from the feed roll last named. 40

50

2. In a stamp vending machine, the combination of a pair of feed rolls between which the stamps are inserted and delivered, means for turning said feed rolls including an oscillating pawl carrier movable around the shaft of one of said rolls and a ratchet wheel fast on said shaft, a spring interacting with said pawl carrier and rendering the same normally retracted, a pair of stops interacting alternately with a part of said pawl carrier, and means for locking and unlocking said pawl carrier, substantially as hereinbefore specified. 55

60

In witness whereof I have hereunto set my hand in the presence of two witnesses, this 23rd day of January, 1908. 65

E. E. WIGZELL.
